FLUID HEATER

Carlos Videche, San Jose, Costa Rica

Application April 9, 1948, Serial No. 20,073

5 Claims. (Cl. 219—40)

1

My invention relates to fluid heaters and more particularly to fluid heaters of the instantaneous type.

One of the objects of my invention is the construction of a compact, simple, inexpensive fluid heater of the instantaneous type which is positive in operation and easy to use, there being no moving parts employed in the unit itself.

Another object of the invention is the provision of an instantaneous fluid heater in which the fluid is in circuit with an electrical current and more particularly employing the use of a plurality of closely spaced electrodes connected in an electrical circuit and causing the fluid to flow in circuit around and between said electrodes in a continuous tortuous path.

A further object of the invention resides in a construction by which the fluid to be heated is caused to contact substantially the entire electrode area of the device.

A further object of the invention is the provision of a device of this kind which by virtue of the fluid to be heated being in circuit, renders the device substantially automatic in operation, that is, by causing the fluid to flow in contact with the electrodes the electrical circuit is thereby established, and by terminating such flow the electrical circuit is broken.

A still further object of the invention is the provision of a fluid heater of the instantaneous type by which the desired temperature of the heated fluid may be controlled by controlling the flow of the fluid through a unit of given electrode area.

Another object consists in the provision of a fluid heater of the type described which can, if desired, be placed in more or less continuous operation over long periods of time.

A still further object of the invention resides in a construction which is not only simple but which is sturdy and safe to use under operating conditions.

Other objects and advantages of my invention will become apparent as the following description of several embodiments thereof progresses, reference being made to the accompanying drawings in which like reference characters are employed to designate like parts throughout the same.

In the drawings:

Figure 1 is a distended view in perspective of one form of my invention.

Figure 2 is an end view of the assembled unit shown in Figure 1.

Figure 3 is a section taken on line 3—3 of Figure 2.

2

Figure 4 is a section taken on line 4—4 of Figure 2.

Figure 5 is an end view of a modified form of my invention.

Figure 6 is a transverse section taken on line 6—6 of Figure 5.

Figure 7 is a plan view of a further modified form of my invention.

Figure 8 is a vertical longitudinal section of the form shown in Figure 7 and is taken on line 8—8 of Figure 9, and

Figure 9 is a transverse section taken on line 9—9 of Figure 8.

Referring first to Figures 1 to 4 inclusive I will proceed to describe the form of the invention disclosed therein.

This embodiment of my invention comprises a type of fluid heater unit in which the fluid inlet and outlet are coaxially arranged near the periphery of the device and in which the fluid is disbursed or guided over substantially the entire area of adjacent sides of adjacent electrodes and thence in contact with adjacent sides of successive adjacent electrodes in a series, alternate electrodes being connected to the live side of a source of electrical energy, and the remaining alternate electrodes and the casing of the device being connected to ground.

More specifically, in referring to Figures 1 to 4 inclusive I have provided a casing 1 having a fluid inlet 2 and a fluid outlet 3 co-axially arranged near the periphery of the casing. The inlet may be suitably threaded as shown for connection with a source of fluid to be heated, and likewise the outlet may also be threaded as shown for connection with a pipe line whereby the heated fluid may be dispensed where desired.

Within the casing 1 are mounted a series of plates or discs 4 and 5, the discs 4 being larger in diameter than the discs 5 and adapted to be secured in spaced relation within the casing 1 and in peripheral contact with the casing as shown in Figure 3. The discs 4 may be anchored in place in the casing by means of soldering, brazing or the like so that all of the discs 4 will be connected to ground.

The discs 5 being of less diameter than the discs 4 are supported in the casing 1 out of contact with the casing and with the adjacent discs 4 between which they are supported in spaced parallel relation.

The discs 4 are provided with a plurality of openings 6 at substantially equally spaced intervals near their peripheries for receiving the rivets 7. The rivets 7 also extend through enlarged

aligned openings 8 in the discs 5 in which are mounted the insulating washers 9, the headed end 10 of the rivets engaging the outer surface of the outermost disc 4 while the opposite end of the respective rivet passes through the end wall of the casing 1 and is peened over or headed as at 12, thus locking the respective alternate discs 4 and 5 in a spaced series within the casing. In addition to the insulating washers 9, there may be provided spacing washers of insulating material 13 through which the rivets 7 pass and which are located between the adjacent respective discs 4 and 5 as shown.

The discs 4 are also provided with an enlarged opening 14 in axial alignment with the axes of the inlet and outlet 2 and 3 respectively when the said discs are mounted in the casing. These enlarged openings are for the purpose of conveying the fluid from one side of the respective discs 4 to the opposite side thereof as will be explained more fully hereinafter.

The discs 5 are each provided with aligned threaded openings 15 for receiving a large screw or the like 16. These openings are located when the device is assembled, in substantial axial alignment with the openings 14; therefore the screw 16 in connecting the discs 5 will pass through the openings 14 of the several discs 4 out of engagement with the walls of the openings 14.

Each of the discs 5 is provided with a plurality of ribs 17 of electrical insulating material on each of its opposite surfaces, these ribs extending substantially in a radial direction and diverging outwardly from near the respective openings 15 in these discs to a point near the periphery thereof as indicated in Figures 1 and 2, the intermediate rib 17¹ being interrupted near the opening 8 in each of the discs 5 as illustrated. Arranged at a plurality of places around the peripheries of the discs 5 are a plurality of spacing members 18 of insulating material. These members are secured to the discs on opposite sides thereof as illustrated.

One of the discs 5 is provided with a binding post 19 which extends outwardly through the casing 1 through an enlarged opening 20 therein as illustrated in Figures 1 and 3, so that this binding post will be free of contact with any part of the casing. To further insure insulation of the binding post from the casing, an insulating washer 21 is provided to overlie the casing wall adjacent the opening 20. A metallic washer and a nut are provided for the binding post whereby an electrical conductor connected with a source of electrical energy may be secured thereto. The outer grounded disc 4, a portion of which lies adjacent the binding post 19, is deformed so as to be spaced from the adjacent surface of the binding post 19, as indicated in Figure 3.

From the above description it will be seen that the assembled unit will provide a structure wherein a fluid to be heated will enter at 2 and pass through the opening 14 in the first grounded disc 4 (to the left in Figures 1 and 3) to the opposite side of this disc. The course then will be between the diverging ribs 17 and 17¹ and in contact with the adjacent surfaces of the first disc 5 and the adjacent disc 4, contacting substantially the entire area of the adjacent faces of these two discs or electrodes, and then flowing over the peripheral edge of the first disc 5 whereupon it will be caused to flow in contact with the adjacent surfaces of the first disc 5 and the second disc 4, thence through the opening 14 in the second disc 4 and downwardly in contact with sub-

stantially the entire adjacent surfaces of the second disc 4 and the second disc 5, between and around the ribs 17 and 17¹ thereof, whereupon the fluid will flow over the peripheral edge of the second disc 5, thence out through the opening 24 which may be restricted as shown and then through the outlet 3. Since the alternate discs 4 are secured along these peripheral edges to the inner circumferential wall of the casing 1, the fluid can only flow past these discs through the opening 14.

While I have illustrated in Figure 1 a device having a limited number of alternate discs 4 and 5, I do not intend to be limited to the number shown, inasmuch as under certain other conditions of use it may be desired to employ a greater or lesser number of pairs of discs depending upon the volume of fluid to be heated.

Referring now more particularly to Figures 5 and 6 of the drawings, I have illustrated therein another embodiment of this invention which in some respects is similar to the embodiment just described, but which differs primarily in that the inlet and outlet connections for the fluid, while in axial alignment, are arranged to be in substantial axial alignment also with the discs of the unit, as distinguished from the arrangement shown in Figures 1 to 4 inclusive. Furthermore in the present embodiment I have provided a different type of means for causing the fluid to contact substantially the entire surface area of the respective discs.

The unit comprises a casing 31 having inlet and outlet threaded couplings 32 and 33 respectively. The casing 31 comprises a receptacle which may be drawn from a sheet of metal and is provided with an outlet opening 34 in its wall 35 communicating with the outlet 33. The cover plate 36 when assembled may be secured to and sealed in the casing by welding, brazing or by other suitable means along its peripheral edges as at 37. The cover is provided with a central axial opening 38 of a diameter substantially that of the fitting 32 with which it communicates. Contrasted to the size of the opening 38 it will be noted that the opening 34, which is in substantial axial alignment therewith, is restricted.

Within the casing 31 are mounted a plurality of metal discs in alternative fashion and in spaced relation as indicated at 39 and 40 respectively, the alternate discs 39 being supported axially on a threaded member 41 operating in threaded openings in these discs. The alternate discs 40 are of greater diameter and are provided with enlarged axial openings 42 to permit the passage of fluid axially through these discs as will be described more fully hereinafter, and to permit passage of the member 41 out of contact with the walls of these openings. The peripheral edges of the discs 40 are secured to the inner peripheral wall of the casing 31 as shown, while the peripheral edges of the discs 39 are spaced from this inner wall.

Interposed between the respective alternate discs 39 and 40 and between the end disc or plate 36 and the adjacent disc 39 and also between the bottom wall 35 and the adjacent disc 39, are the spacer and fluid directing members 43. These members are formed of electrical insulating material and may be assembled and secured to the opposite faces of either the discs 39 or 40 before assembly in the casing 31.

These members comprise a peripheral portion 43 from which the ribs 44 project radially inwardly from near the periphery of the member

and terminate short of a substantially circular portion 45 of the member which is arranged coaxially around the openings 42. Extending substantially radially outward of the circular portion 45 but terminating short of the peripheral portion of the member 43 are a plurality of ribs 46. A rib 47 connects the circular portion 45 with the peripheral portion 43, while the peripheral portion 43 terminates short of the junction of the rib 47 with the opposite end of the peripheral portion 43 as indicated at 48.

Thus it will be seen referring particularly to Figure 5, that fluid entering the inlet 32 will pass between the end plate 36 and the adjacent disc 39 and thence through the opening 49 provided in the substantially circular portion of the insulating member 45. The fluid will thence flow in a counterclockwise direction first upwardly and thence around the successive ribs 46 and 44 respectively and will thereby be guided toward the opening 50 where it will be caused to spill or flow over the peripheral edge 51 of the adjacent disc 39. In this circuitous travel of the fluid it will be seen that it will be distributed over substantially the entire surface area of the adjacent walls of the end plate 36 and the adjacent disc 39.

In Figure 6 in which the device is illustrated in cross-section, the arrows indicate the direction of flow of the fluid between and around each of the successive discs in the series comprising the unit, in each stage being guided or directed over substantially the entire surface area of the respective adjacent discs. As further indicated by the arrows in Figure 6 the fluid will find its exit through the restricted opening 34 in the bottom wall 35 of the casing and will thence be directed outwardly through the outlet 33.

In Figures 7, 8 and 9 I have illustrated a further embodiment of the present invention which comprises an outer casing 60 preferably in the form of an elongated tube having a fluid inlet 61 and a fluid outlet 62 connected therewith. Within this tube are mounted a plurality of alternate discs or electrodes 63 and 64, the electrodes 64 being of greater diameter than the discs 63 and contacting at their peripheral edges with the metal casing or tube 60. Each of the discs 64 is provided with an enlarged central opening 65 through which a bolt 66 is adapted to pass. The alternate discs 63 are provided with axial openings for receiving the bolt 66 on which these discs are supported. The discs 63 are further supported at spaced intervals along their peripheries by means of insulating blocks 67 having suitable grooves 68 therein for receiving the outer edges of these discs. The insulating blocks 67 not only support the discs 63 radially within the tube 60, but further serve to properly space them from the adjacent discs 64.

The outer disc 64¹ is provided with an opening 69 whereby the fluid to be heated may enter the succession of spaced discs, whereas the end disc 70 is provided with an outlet opening 71 which preferably is restricted as compared with the diameter of the opening 69. The bolt 66 is insulated from the end plates 64¹ and 70 by means of its insulating washers 72 and 73 respectively and is provided on one end with a nut 74 operating against the metallic washer 75 and against the insulating washer 72 whereby the respective discs may be clamped together in spaced relation and assembled as a unit. The bolt 66 also serves as a binding post for connecting a conductor 76 which leads from a binding post 77 mounted on but insulated from the tubular

casing 60. A source of electrical energy may be connected with the binding post 77 while the casing 60 is preferably grounded as at 78.

In this form of the invention it will be seen that the mode of assembly of the unit may be somewhat simplified in that the discs may be assembled in proper relationship and then inserted in the open end of the tubular casing 60 to which subsequently may be secured at its ends the respective inlet and outlet members 61 and 62, by means of welding or the like as at 79.

From the foregoing description of this invention and its several modifications it will be seen that I have provided a relatively simple electrically operated heating unit for fluids such as water, in which there are provided spaced electrodes between which the fluid is caused to travel and circulate in contact with these electrodes in a somewhat circuitous path between the inlet and the outlet of the devices. The principle of operation is substantially the same in each of the forms illustrated and described. By means of this invention these devices lend themselves to economical manufacture and provide means whereby water or other fluid may be heated to substantially any degree desired as it flows through the unit, such heating being substantially instantaneous in its nature. It will also be seen that by terminating or shutting off the flow of fluid through the unit, the device becomes inactive electrically since the fluid must be present to complete the electrical circuit between the adjacent electrodes through the unit. Thus the device possesses a high safety factor in its operation.

Various changes may be made in the details of construction and arrangement of parts without departing from the spirit of the invention or the scope of the appended claims.

I claim:

1. An electrical fluid heater of the fluid-in-circuit type comprising a housing, a plurality of spaced apart plate electrodes in said housing, alternate plates being connected together to ground and the remaining plates adapted to be connected to a source of electrical energy, a fluid inlet in said housing, a fluid outlet therefor, and means intermediate adjacent plates for directing the fluid to be heated therebetween and in contact with substantially the entire surface area of said plates, said means causing said fluid to move over the plate surfaces in a direction substantially radial to its initial point of contact with said surfaces.
2. In a fluid heater, a casing, a fluid inlet, a fluid outlet, a plurality of plate electrodes in said casing and spaced apart to permit the fluid to be heated to contact and flow over the adjacent surfaces of said plates, alternate plates having electrical connection with a source of electrical energy and the remaining plates being grounded to said casing, said fluid completing an electrical circuit between said plates, and means between each of the adjacent plates of the device and disposed in a direction substantially radial to the axis of the fluid inlet whereby to distribute the fluid over substantially the entire surface area of said plates and toward the peripheries of certain of said plates.
3. In a fluid heater, a casing, a fluid inlet, a fluid outlet, a plurality of plate electrodes in said casing and spaced apart to permit the fluid to be heated to contact and flow over the adjacent surfaces of said plates, alternate plates having electrical connection with a source of electrical

energy and the remaining plates being grounded to said casing, said fluid completing an electrical circuit between said plates, and means between each of the adjacent plates of the device and disposed in a direction substantially radial to the axis of the fluid inlet whereby to distribute the fluid over substantially the entire surface area of said plates and toward the peripheries of certain of said plates and thence around said peripheries and toward said inlet axis of the next adjacent plate.

4. An electrical fluid heater of the fluid-in-circuit type comprising a housing, a plurality of spaced apart plate electrodes in said housing, alternate plates being connected together to ground and the remaining plates adapted to be connected to a source of electrical energy, a fluid inlet in said housing, a fluid outlet therefor, and means intermediate adjacent plates for directing the fluid to be heated therebetween and in contact with substantially the entire surface area of said plates, said means causing said fluid to move over the plate surfaces in a direction substantially radial to its initial point of contact with said surfaces, said means comprising a spacer element of electrical insulation material.

5. In a fluid heater, a casing, a fluid inlet, a

fluid outlet, a plurality of plate electrodes in said casing and spaced apart to permit the fluid to be heated to contact and flow over the adjacent surfaces of said plates, alternate plates having electrical connection with a source of electrical energy and the remaining plates being grounded to said casing, said fluid completing an electrical circuit between said plates, and means between each of the adjacent plates of the device whereby to distribute the fluid over substantially the entire surface area of said plates and toward the peripheries of certain of said plates, said means comprising an electrical insulating spacer member having a plurality of arms radially disposed with respect to said fluid inlet.
